US00D626094S

(12) **United States Design Patent**
Alexander et al.

(10) **Patent No.:** US D626,094 S
(45) **Date of Patent:** ** Oct. 26, 2010

(54) **HEAT SINK UNIT FOR USE WITH A
REMOVABLE LED LIGHT MODULE**

D383,236 S 9/1997 Krogman
D437,449 S 2/2001 Soller
D437,652 S 2/2001 Uhler et al.

(75) Inventors: **Clayton Alexander**, Westlake Village, CA (US); **Brandon Mundell**, Thousand Oaks, CA (US); **Robert Rippey, III**, Westlake Village, CA (US)

(Continued)

(73) Assignee: **Journée Lighting, Inc.**, Westlake Village, CA (US)

WO DM/057383 9/2001

(**) Term: **14 Years**

(21) Appl. No.: **29/358,277**

(22) Filed: **Mar. 24, 2010**

(57) **CLAIM**

(51) **LOC (9) Cl.** 13-03

The ornamental design for a heat sink unit for use with a

removable LED light module, as shown and described.

DESCRIPTION

FIG. 1 is a perspective bottom view of the heat sink unit.

FIG. 2 is a perspective top view of the heat sink unit in FIG. 1.

FIG. 3 is a bottom view of the heat sink unit in FIG. 1.

FIG. 4 is a top view of the heat sink unit in FIG. 1.

FIG. 5 is a side view of the heat sink unit in FIG. 1.

FIG. 6 is another side view of the heat sink unit in FIG. 1, rotated 90 degrees from the view in FIG. 5.

FIG. 7 is another side view of the heat sink unit in FIG. 1, rotated 90 degrees from the view in FIG. 6; and,

FIG. 8 is another side view of the heat sink unit in FIG. 1, rotated 90 degrees from the view in FIG. 7.

The broken lines are for illustrative purposes only and form no part of the claimed design.
